UNITED STATES PATENT OFFICE.

JOHN RAPHAEL ROGERS, OF BROOKLYN, NEW YORK, ASSIGNOR TO MERGENTHALER LINOTYPE COMPANY, A CORPORATION OF NEW YORK.

TYPOGRAPHICAL MACHINE.

1,115,109.

Specification of Letters Patent. Patented Oct. 27, 1914.

Application filed July 24, 1911. Serial No. 640,081.

To all whom it may concern:

Be it known that I, JOHN RAPHAEL ROGERS, a citizen of the United States, and a resident of Brooklyn, county of Kings, and State of New York, have invented a new and useful Improvement in Typographical Machines, of which the following is a specification.

My invention relates to typographical machines, and more particularly to that class thereof known to the public under the name "linotype" and of the general organization illustrated and described in Letters Patent of the United States to O. Mergenthaler, No. 436,532.

In the particular respects herein illustrated and described, the invention relates to such a machine having a plurality of magazines and distributing mechanism therefor, and more specifically to that type thereof wherein are provided appliances for securing a preliminary separation of the matrices into their respective fonts, after which they are conveyed to the appropriate magazines and individually distributed. Such a mechanism is disclosed in my Letters Patent No. 890,303, and, in so far as the font separating means are concerned, also in my pending application filed July 20, 1911 Serial No. 639,588. Generally speaking, after the matrices have been separated into fonts in the manner described in my said Letters Patent and application, they are conveyed through a plurality of properly constructed tubes to a corresponding plurality of distributor boxes of the same general form and construction as illustrated in the United States Letters Patent to D. S. Kennedy, No. 849,795. From these boxes in turn, the matrices are delivered to their respective magazines, each of which is provided with an ordinary distributing mechanism of the Mergenthaler type, consisting of a longitudinally toothed bar and adjacent feed screws to advance the matrices along the same, as in U. S. Letters Patent No. 347,629.

As previously set forth, the general organization to which my invention and improvements relate comprises font separating means, a plurality of distributing boxes and a corresponding plurality of tubes which convey the matrices from the font separating means to the boxes. It will be understood, of course, that the number of boxes and connected tubes will correspond to the

number of magazines with which the machine is equipped, in the present instance, four such boxes and their connected devices being provided for.

In addition to the general organization as above set forth, my invention also relates to specific improvements in the individual members thereof, such for instance as the construction of the tubes, of the matrix separator which delivers the matrices from the box to the distributor screws, of the means for actuating this matrix separator, of the means for locking the tubes in position, and of the box itself.

These and other improvements and modifications will be apparent from the accompanying drawings and detailed description and will be finally pointed out in the claims.

In the drawings I have shown my improvements as applied in preferred form, but many changes and modifications may be made therein, or they may be applied to other parts of the distributing mechanism or to distributing mechanisms of different form, without departing from its spirit; and generally speaking I desire it to be understood that I do not limit myself to any specific form or embodiment except in so far as such limitations are specified in the claims.

In the accompanying drawings: Figure 1 is a perspective view showing the connection of the font separating means, tubes and distributor boxes; Fig. 2 is a perspective view of a distributor box detached; Fig. 3 is a bottom view of the distributor box; Fig. 4 is an end view of the eccentric means employed for actuating the matrix separator; Fig. 5 is a perspective view of the distributor boxes and connected devices, partly broken away and partly in section; Fig. 6 is a perspective view of one of the tubes; partly broken away; Fig. 7 is a longitudinal sectional view of the tube; and Fig. 8 is a face view of the tube.

Referring to the drawings, the font separating devices A are shown of the general form and character set forth in my previously mentioned Letters Patent and application, and as their precise construction and operation are immaterial so far as the present invention is concerned, further description thereof will not be given herein. After the font separation of the matrices X, they are conveyed through a plurality of tubes

B to a corresponding plurality of distributor boxes C, from which in turn they are delivered to the regular distributing rails and screws and thereby conveyed to their respective magazine channels in the manner set forth in the previously mentioned Mengenthaler Patent No. 347,629. As the matrices X (see Fig. 5) pass downward through the tube B into the distributor box C, they are caused to traverse an irregularly shaped or tortuous passage, whereby they are delivered to and pass along the bar F. Each individual matrix is then acted upon by a separating mechanism comprising a pair of pawls D⁴, D⁴, mounted on links D³, D³, connected to a pivoted lever D², which in turn is given a reciprocal motion by a pivoted arm D, all substantially in the manner set forth in the previously mentioned Kennedy Patent No. 849,795. By this construction the matrices are separated individually into the path of the threads on the usual distributor screws E, which advance them for distribution to the appropriate magazine channels in the manner well understood in the art. The arm D is pivotally mounted at D¹ on the box C and is reciprocated by the connected piece D⁶, which is formed with an enlarged aperture D¹⁵, shown in dotted lines in Fig. 4. The aperture D¹⁵ normally engages the reduced conical point E² of the pintle E¹, which is connected to and forms a continuation of one of the distributor screws E, as indicated by dotted lines in Fig. 5. Referring again to Fig. 4, it will be noted that the conical point E² is eccentrically located upon the pintle E¹, and therefore that the rotation of the screw E and pintle E¹, through the engagement of the point E² with the aperture D¹⁵ in the connected piece D⁶, will effect the necessary reciprocation of the arm to actuate the matrix separating device. As previously stated, the part E² is conically shaped or pointed, and this feature is of advantage in that it permits the ready removal and replacement of the distributor box C without the necessity for paying especial attention to the disconnection and connection of the means for actuating the matrix separator. In other words, the removal of the box C disengages the piece D⁶ from the point E², and when the box is replaced the point E² readily finds and passes into the aperture D¹⁵ without manual adjustment and because of its conical or pointed form. It sometimes occurs in the operation of the matrix separator that the matrix is not presented in proper position thereto or that it becomes jammed, and I therefore provide the arm D with an intermediate spring or elastic section D⁷ which allows the parts to yield, and thus prevents their breakage or disarrangement.

65. The boxes C, as previously stated, are in-

dividually of the same general character as set forth in the Kennedy Patent No. 849,795, and are so constructed that they may be readily slid into and held in normal operative position between the projecting frame pieces C², which are furnished with the locking arms or latches C¹. In the present instance, however, the box C is provided with a deflecting corner C⁵ (see Figs. 2 and 5), the corner C⁵ being detachably secured to the main portion of the box. To this end I form the corner C⁵ with studs or projections C⁶, which engage in corresponding slots C⁷ in the sides of the box. When the boxes are in normal position, as shown in Figs. 1 and 5, the corners C⁵ are held rigidly by reason of their abutment against the machine frame-work. When, however, the box is removed, the corner C⁵ may be readily detached therefrom, as shown in Fig. 2. This feature of detachability is of importance in that it permits ready access to the interior of the box for the manipulation of the interior parts or for the necessary cleaning thereof.

90. The tubes B are of the peculiar shape and construction particularly illustrated in Figs. 1, 6, 7 and 8, and are located in proper relation to the font separating means A and distributor boxes C in cuts C¹⁰ formed in the projecting frame pieces C², being held therein by suitable locking devices. These locking devices comprise a projection or flange B³ on each of the tubes, and pivoted latches B⁴ on the frame which are turned thereover when the tubes are mounted in the cuts C¹⁰, thus holding them securely in operative position, see Fig. 1. Another feature in connection with the tubes is the provision of means to hold the matrix in proper relation to the side thereof as it descends to the distributor box. In the ordinary operation of the machine, difficulty has been sometimes experienced because of the tendency of the matrix to turn and twist, or to leave the side of the tube, and a further difficulty arises from the fact that due to the different thicknesses of matrices, guiding and holding means must be employed which will adapt themselves to such varying thicknesses. To this end, I provide within the tubes B one or more guiding flaps B¹ pivoted thereto at B². These flaps are so shaped and proportioned as to conform to the contour of the tube and are normally held by gravity in close relation to the side thereof in the path of the descending matrices. As the matrices X X descend through the tube (see Fig. 7), they move the flaps outwardly in passing, after which they return to their normal position. The resistance of the flaps to the movement of the matrices is not sufficient to check the momentum of the latter, and moreover, due to the pivotal arrangement thereof, it is imma-

terial whether the matrix be thick or thin, as clearly shown in Fig. 7.

Having thus described my invention, its construction and mode of operation, what I claim and desire to secure by Letters Patent of the United States is as follows:—

1. In a typographical machine, the combination of a plurality of distributors, a font separator, and a plurality of chutes leading from the font separator to the several distributors, the said chutes being detachably mounted in the framework so as to be freely removable at will and so located as to permit such removal without disturbing the other parts.

2. In a typographical machine, the combination of a plurality of distributors, a font separator, and a plurality of chutes leading from the font separator to the several distributors, the said chutes being each detachably mounted in the framework so as to be freely removable independently of one another and so located as to permit such removal without disturbing the other parts.

3. In a typographical machine comprising distributing mechanism, the combination of the matrix conveying tube B provided with the flange B³, and the framework formed with the cut C¹⁰ and provided with the locking device B⁴ to engage the flange B³.

4. In a typographical machine, the combination of the frame work formed with the cut C¹⁰, and the distributing tube B located in said cut and removable laterally therefrom, together with locking means, releasable at will to hold said tube in position in said cut.

5. In a typographical machine comprising distributing mechanism, a distributor box provided with a deflecting corner detachably secured thereto.

6. In a typographical machine comprising distributing mechanism, a distributor box provided with a deflecting corner detachably secured thereto, one of the parts being formed with slots and the other with correspondingly located studs.

7. In a typographical machine comprising distributing mechanism, the box C formed with slots C⁷ and having a detachable deflecting corner C⁵ provided with the studs C⁶.

8. In a typographical machine, the combination of distributing mechanism, a separating finger to control the delivery of the matrices thereto, and a reciprocating arm or lever actuated positively in both directions for operating the finger, the said operating arm being formed in part of spring or elastic material to permit it to yield in the event of undue resistance.

9. In a typographical machine, the combination of distributing mechanism, a reciprocating separating finger to control

the delivery of the matrices thereto, and a pivoted arm or lever actuated positively in both directions for operating the separating finger, the said arm being formed with an elastic or spring section D⁷ to permit it to yield in the event of undue resistance.

10. In a typographical machine, the combination of distributing mechanism, two alternately acting pawls to control the delivery of the matrices thereto, and an arm or lever actuated positively in both directions for operating the pawls, the said arm being adapted to yield when undue resistance is offered to either of the two pawls.

11. In a typographical machine comprising distributing mechanism, means for controlling the delivery of the matrices to the distributing mechanism, the said means including an eccentrically located member and a part operated thereby and formed with an aperture engaging it, the said eccentrically located member being formed with a conical point to permit of its ready engagement with the aperture.

12. In a typographical machine comprising distributing mechanism, means for controlling the delivery of the matrices to the distributing mechanism, the said means comprising the eccentrically located and conically formed point E² and the piece D³ formed with the aperture D⁴.

13. In a typographical machine, the combination of the frame work and distributing mechanism comprising the matrix conveying tube B mounted thereto, the said parts being formed with interlocking portions disengageable at will to permit the ready removal and replacement of the tube.

14. In a typographical machine, the combination of distributing mechanism comprising a matrix conveying tube formed with a flange or projection and a movable latch mounted on the frame work to engage and hold the tube in position thereon.

15. The distributor box C having a passage therethrough for the matrices, and formed with a deflecting corner or guide forming one of the walls of the passage and movable at will from its operative position to give access to said passage.

16. In a typographical machine, the combination of distributing mechanism comprising a rotary screw, and means for controlling the delivery of matrices to the distributing mechanism, the said means comprising a reciprocating finger and an operating lever therefor, the said lever being eccentrically connected to the end of the distributor screw so as to be actuated thereby.

17. In a typographical machine, the combination of distributing mechanism comprising a rotary distributor screw, a removable distributor box provided with a reciprocating finger to control the passage of the matrices therethrough, and also a lever for

operating said finger, the said screw being formed at its end with an eccentrically mounted pin adapted to engage in a recess in the operating lever so as to allow the removal and replacement of the distributor box at will.

In testimony whereof I hereunto set my

hand this 22nd day of July, 1911, in the presence of two attesting witnesses.

JOHN RAPHAEL ROGERS.
